UNITED STATES PATENT OFFICE.

LEWIS H. PHELPS, OF WESTFIELD, NEW JERSEY.

REGULATOR FOR FLUID-HEATING SYSTEMS.

1,047,443.

Specification of Letters Patent. Patented Dec. 17, 1912.

Application filed February 15, 1910. Serial No. 544,040.

To all whom it may concern:

Be it known that I, LEWIS H. PHELPS, a citizen of the United States, residing at Westfield, in the county of Union and State 5 of New Jersey, have invented certain new and useful Improvements in Regulators for Fluid-Heating Systems, of which the following is a specification.

The invention relates to improvements in fluid expansion regulators for heating systems and has particular reference to apparatus adapted to control the expansion of fluids under pressure in hot water heating systems.

15 The object of the invention is the providing of apparatus adapted to be mounted in the system of piping of a hot water heating system adapted to control the expansion of fluids in a system of that nature and maintain said system under a predetermined degree of pressure and means whereby after the expansion of the fluids in said system the said expanded fluids are permitted to return from a suitable fluid expansion retaining means through the regulating apparatus to the system.

20 In the following is described in connection with the accompanying drawings one embodiment of the invention, the features 30 thereof being more particularly pointed out hereinafter in the claims.

In the drawings,—Figure 1 is a vertical section of the apparatus with parts thereof shown in elevation. Fig. 2 is a section on 35 the line 5—5 of Fig. 1, showing a plan view of the slide valve; and Fig. 3 is a bottom view of said valve.

Similar numerals of reference indicate similar parts throughout the several views.

40 In the drawings 30 designates a casing provided at its lower end with an internally threaded nipple 31 adapted to receive fluid pipe connection 32 and at its side thereof near the top a nipple 33 adapted to receive 45 fluid expansion pipe connection 34, the top of said casing being threaded internally to receive cap or cover 35 having formed thereon a boss 36 provided with a bearing 37 the object of which is hereinafter described.

50 Said casing 30 has cast therewith, a web 38 provided at its center with a depending valve casing 39 and on its face a valve seat 40 beveled to receive ground valve head 41 on valve 42 which in turn has mounted there- 55 in a threaded plug 43 carrying spindle 44 the upper end thereof finding bearing, guid-

ance and support in bearing 37 in cap 35 and boss 36, said spindle in turn carrying weight 45, the object of which is to provide means for holding valve 42 in its normal position before expansion has taken place throughout a system of this nature. When the regulator is in its normal position or when valve 42 is closed web 38 divides the interior recesses of casing 30 into two independent fluid chambers 46 and 47. Valve 42 has cut therein a plurality of ports 48 communicating with chamber 46 and auxiliary ports 49 which permit the fluids during expansion to pass from said chamber 46 through said ports into chamber 47 thence through pipe connection 34 to a suitable expansion tank (said tank is not shown herein as it forms no part of this invention). Valve 42 has also cut therein return ports 50 communicating with chamber 51 the walls thereof having formed thereon a valve seat 52 having mounted therein a valve 53 adapted to control the return passage of fluids from chamber 47 through ports 50 into ports 48 after the expansion has taken place or when the valve 42 is again reseated by weight 45 permitting the expanded fluids to again re-enter the system.

The operation of the device is as follows: 85 Before the fluids expand in hot water heating systems the regulator is held in substantially normal position and immediately upon the generation of heat throughout the said means of radiation and when, as a matter of illustration, the expansion reaches the point of substantially ten pounds pressure, the expansion valve is moved vertically upwardly from its valve seat permitting the 90 fluids under expansion to pass into the upper fluid expansion chamber. It will be obvious from a study of the structure that the return fluid ports 50 and the valve 53 form a substantial part of valve 42, the expansion of the fluids being controlled by 95 means of the valve 42 which is in turn controlled by means of the pressure weight 45, the pressure of which must necessarily be ascertained before sealing the system. The plurality of fluid expansion ports and return fluid ports provides a means more readily acquiring a perfect expansion of the fluids under pressure, also one wherein the return of the expanded fluids is had thus obviating any possible interruption of fluids 100 either during expansion or the return thereof through the regulator.

What I claim and desire to secure by Letters Patent of the United States is:—

1. A device of the character described comprising a casing having cast integrally therewith at its center and extending diametrically across said casing a web provided with a valve seat and a depending circular wall dividing said casing into two independent chambers, said wall providing a fluid passageway adapted to form a means of communication between said chambers, a cover for said casing provided with a boss having formed therein a bearing adapted to form a guide reception means, a fluid inlet pipe connection communicating with one of said chambers, a fluid outlet pipe connection communicating with the other of said chambers, a fluid expansion valve mounted in said valve seat and adapted to open in the direction of the flow toward the fluid outlet pipe and having formed therein fluid expansion passages adapted to form means of communication between said independent chambers when said valve is in its lifted or open position, a spindle mounted on said valve its upper end engaging the bearing in said cover, a weight mounted on said spindle, said valve having an auxiliary fluid return passage cut therein to form means of communication between one of said chambers and said fluid expansion passages when said valve is in its normal position, said return passage having formed therein a valve seat, and an auxiliary valve opening in the direction of the flow toward the fluid inlet pipe connection and normally resting within said seat adapted to control the passage of return fluids therethrough.
2. A device of the character described including a casing having cast integrally therewith at its center a web provided on its upper surface with a valve seat and on its lower surface with a depending circular wall dividing said casing into two independent chambers, said wall providing a fluid passageway adapted to form a means of communication between said chambers, a cover for said casing having cast integrally therewith a depending boss having cut therein a bearing adapted to form a guide reception means, a fluid inlet pipe connection communicating with one of said chambers, a fluid outlet connection communicating with the other of said chambers, a fluid expansion valve normally resting in said valve seat and having cut therein a plurality of expansion passages adapted to

form a means of communication between said chambers when said valve is in its lifted or open position said valve being adapted to open in the direction of the flow toward the fluid outlet pipe connection, a spindle mounted on said valve engaging the reception bearing in the said cover, a weight mounted on said spindle, said valve having an auxiliary fluid return passage cut therein to form means of communication between the upper of said chambers and said valve expansion passages when said valve is in its normal position, said auxiliary fluid return passage having formed therein a valve seat, and an auxiliary valve free to move vertically upwardly with relation to said passage in the direction of the flow toward the fluid inlet pipe connection adapted to control the passage of return fluids from the upper to the lower of said chambers.

3. The combination with a casing, a web dividing the casing into two chambers and having a depending valve bearing, said casing having a fluid inlet in one chamber and a fluid outlet in the other chamber; of a lift valve slideable in said bearing having a passage communicating with the fluid inlet chamber and a passage communicating with the fluid outlet chamber, said passages being in communication with each other, a check valve between said passages, said lift valve having an auxiliary passage through its wall connecting with the passage leading to the inlet chamber, said auxiliary passage controlled by the movement of the lift valve with respect to its bearing, and means to load the valve.

4. The combination with a casing, a web dividing the casing into inlet and outlet chambers, said web having a valve bearing; of a valve slideable in said bearing and having a set of passages opening into the inlet chamber and a set of passages opening into the outlet chamber and communicating with the first mentioned passages, a check valve controlling communication between said sets of passages, and said slide valve having auxiliary ports through its wall communicating with the first set of ports and controlled by the movement of the slide valve.

In testimony whereof I have hereunto signed my name in the presence of two subscribing witnesses.

LEWIS H. PHELPS.
